UNITED STATES PATENT OFFICE.

FRANK P. KEMON, OF ATLANTIC CITY, NEW JERSEY.

FORM FOR CONCRETE CONSTRUCTION.

1,212,499.

Specification of Letters Patent. Patented Jan. 16, 1917.

Application filed March 30, 1916. Serial No. 87,769.

To all whom it may concern:

Be it known that I, FRANK P. KEMON, a citizen of the United States, residing at Atlantic City, in the county of Atlantic and State of New Jersey, have invented a new and useful Improvement in Forms for Concrete Construction, of which the following is a specification.

My present invention relates to forms for concrete construction, and more particularly for use in the erecting of straight or battered walls, retaining walls, reservoirs, building foundations and walls, arch bridges, abutments, piers, houses, barns, garages, 15 sewers, tunnels, viaducts, culverts, tanks, silos, grain elevators, etc.

The principal objects of my invention are, first, to provide concrete forms adaptable to all purposes of concrete construction; second, to provide forms embodying elements which so coöperate that erection and dismantling may be accomplished with ease; third, to provide forms avoiding the use of detachable keys, pins or wedges as means for holding the parts in operative relation, but utilizing such devices as bolts and nuts of either the standard type or thumb-nuts, which may be maintained in screw-threaded engagement with the bolts during and after dismantling, thereby rendering the forms inexpensive to provide and maintain them in workable conditions at all times; fourth, to provide forms of such construction that the concrete may be conveyed to the space adjacent or between the form or forms and deposited without drop from a great height; fifth, to provide forms of such construction embodying panels which may be removed at any point in the wall to permit of inspection, 40 or the placing of spouting, etc., therein; sixth, to provide forms of such construction that the panels may be progressively raised with respect to the uprights as the concreting progresses and becomes self-sustaining 45 upon its base, eliminating the necessity of a large number of panels at any particular job; seventh, to provide forms with which standard rolled steel sections may be utilized, thereby enabling the bulk of material 50 to be readily obtained in localities where manufacturing and construction work is in progress; and, eighth, to provide forms utilizing pressed steel sections which are light and durable, and which may be strengthened 55 by wood fillers, or uprights, when desired, such as where standard rolled sections are

not available and transportation rates are high.

Other objects of the invention will appear in the following detailed description, taken in connection with the accompanying drawings, forming a part of this specification and in which drawings:

Figure 1 is an exterior elevation of a form constructed according to my invention, parts being broken away, removed and the view condensed. Fig. 2 is a sectional view on the line 2—2 of Fig. 1. Fig. 3 is an enlarged sectional view transversely of the base and longitudinally of one of the uprights, forming a part of my invention. Fig. 4 is a sectional view on the line 4—4 of Fig. 3. Fig. 5 is a perspective view of the upper portion of one form of main support or upright. Fig. 6 is a fragmentary perspective view of 75 a retainer coöoperating with the support shown in Fig. 5. Fig. 7 is a transverse sectional view showing a modified form of main supports, with portions of panels in operative relation thereto. Fig. 8 is a view 80 similar to Fig. 7 showing a further modification of the main supports, more particularly adapted for drawing form sections together. Fig. 9 is a transverse sectional view through a modified form of corner uprights, 85 with portions of panels in operative relation thereto. Fig. 10 is a perspective view of a wood filler used in connection with a modified form of upright. Fig. 11 is a view 90 similar to Fig. 9 showing means of holding parts in operative relation one to another. Fig. 12 is a view similar to Fig. 9 showing a further modification of a corner upright. Fig. 13 is a view similar to Fig. 7 showing 95 a further modification of an upright to be aligned with other uprights, and more particularly adapted for heavy work. Fig. 14 is a view similar to Fig. 13 showing a lighter construction of said upright. Fig. 15 is a view associated with Fig. 14, showing means 100 for holding parts in operative relation one to another. Fig. 16 is a transverse sectional view through an internal corner upright, showing portions of panels in operative relation thereto. Fig. 17 is a view associated with Fig. 16 showing means for holding parts in operative relation one to another. Fig. 18 is a view similar to Fig. 9 showing a further modification of the corner upright supports, and more particularly 105 adapted for external corners. Fig. 19 is a view similar to Fig. 13, showing a further

modification of an upright to be alined with others. Fig. 20 is a view similar to Fig. 16 showing a further modification of the internal upright corner construction. Fig. 21 is a perspective view of the upper portion of a wood filler to be used more particularly in connection with the form of uprights shown in Fig. 13.

In the drawings, where similar characters refer to similar parts throughout the several views, A designates generally a suitable base, such as a channel section disposed with its web uppermost; B, main supports or uprights formed of single rolled steel sections, or a plurality of sections; C, a cap for the main support; D, panels in abutting relation with and supported by said main supports or uprights; E, retainers, such as angle bars or members of angle sections, for holding the panels C in place; F, securing devices for the retainers by which they are permanently connected with the main supports and held in adjusted position; and, G, ties, longitudinally of the forms.

It has already been purposed to utilize rolled steel sections in concrete forms, as well as pressed steel sections, and such has been brought into practical use, utilizing keys, pins or wedges for holding one part into operative relation to the other.

One of the principal objects of my invention is to avoid the use of such detachable devices, it having been found in practice that where such devices must be removed from engagement with essential parts of the forms, they become lost and a considerable outlay is necessary to replace such special detachable devices when the forms are again set up for practical use.

In the drawings, I have illustrated several modifications of main supports or uprights, to which the invention is applicable, and it is to be appreciated that changes in details may be made without departing from the spirit of my invention, as hereinafter set forth.

The base A may be of any suitable section, preferably a channel, disposed with its webs 22 uppermost, the outer edges of the flanges 23 resting upon the ground. The web of each base is provided with a plurality of perforations 24, one of which is shown in Fig. 3 to facilitate the attachment of uprights B to the base, as hereinafter described.

Referring first to the main supports or uprights, and more particularly to the forms shown in Figs. 1, 2, 3, 4, 5 and 6, they comprise standard rolled I-sections, each including a web 25, longitudinal flanges 26 disposed nearest the "hollow" of the form, and outer flanges 27. Each upright is also provided with a plurality of ways 28, the opposite walls 29 of each way inclining toward the flanges 26. For a purpose to be subsequently set forth, I prefer to form the

ways 28 of L-shape, the longer leg 30 of which is that bounded by walls 29, while the shorter leg 31 extends toward the flanges 27, and is preferably uppermost. In other words, I prefer to dispose the ways 28 in the web 25 of each upright B in such a manner that one leg of each way inclines toward and with its closed end nearest flanges 26.

While I have shown the uprights B, in Fig. 1, as disposed in alined spaced-apart relation, and held rigid at their upper portion by means of cap C, it is to be understood that such cap may be dispensed with under certain conditions. The uprights may be secured to the base A as by angles 32, disposed at either or both sides of the web 25 of each upright, and with one leg 33, of each angle member 32, resting upon the web 22 of the base A. The other leg 34 of each angle 32 abuts against the web 25 of the upright, and both legs are provided with perforations 35 and 36, respectively, the perforation 35 alining with a perforation 24 in the web of the base, while the perforation 36 alines with a perforation 37 in the web 25 of upright B. Through the alined perforations 24 and 35, a bolt 38 is passed, receiving nut 39, whereby the angle 32 is made rigid with the base. Through the alined perforations 36 and 37, a bolt 40 is passed, receiving thumb nut 41, holding the upright rigid with the base. The cap C may also be secured to the uprights in a similar manner, such as by angles 42, clearly shown in Fig. 1.

As to the panels D, they may be of any suitable material, such as pine planking 43, which may or may not be provided with tongues and grooves 44 and 45, respectively, and in heavy work, may be provided with metal plates 46, secured to the wood backing, in any suitable manner, such as by screws 47. In practice, the panels are provided with reduced edge portions 48, which rest against flanges 26, bringing the faces of the panels flush with the faces of said flanges, forming walls of the "hollow" when assembled.

In order to hold the panels in intimate contact with flanges 26, the retainers E are provided. They are preferably of angle section, and in a practical application of my invention, may consist in standard rolled steel angle sections, one leg 48, of each retainer, to rest against the panel D while the other leg 49 rests against the web 25 of the upright. Each retainer is provided with a plurality of perforations 50 so spaced that they may be alined with the ways 28 of the uprights. The securing devices F, which have the dual function of permanently securing the retainers to the uprights, and also hold them in an adjusted position with respect to the panels, may comprise each, a

5 bolt 51 passing through alined perforations 50, and a nut 52, either of the standard type, or a thumb nut, as shown in Fig. 3. If desired, a cotter pin 53 may be passed through 5 and secured in an opening 54 adjacent the end portion of the bolt, so that the nut cannot be removed without first removing the cotter pin, thus preventing accidental separation of the nut and bolt due to vibration.

10 It is to be observed that, with the shank of the bolt engaging the walls of ways 28, and more particularly the inclined walls 29 of said ways, by tapping upon the bolt heads or the upper portions of retainers E, they may be forced into intimate contact with the panels D which action, in turn, forces said panels in tight engagement with the flanges 26. When the nuts 52 are tightened, the 15 panels are held securely in place. This adapts the uprights for use in connection with thick, medium sized, or thin panels, according to the character of the work, said inclined walls 28 enabling the operator to positively move the retainers E either toward or from the flanges 26, while the legs 25 of the ways 28, enable the retainers E to be retracted sufficiently to remove any panel D. Likewise, by releasing the nut 52, re- 20 tracting the retainers E, any panel may be easily raised, enabling the panel to serve as 30 a confining means for the concrete to be placed upon concrete which is already self-sustaining, that is, set, or the bulk of which is supported laterally by the uprights B. 35 This enables the operators to progressively raise the panels D, so that very few are required in proportion to the magnitude of the undertaking.

Referring now to the modification shown 40 in Fig. 7, the upright B' is in the form of a rolled T-section, and is particularly adapted for lighter work. It comprises the web 25, flanges 26 against which the panels D rest, ways 28 in web 25 retainers E and securing devices F. The only difference be- 45 tween this modification and that designated B is the omission of flanges 27, and this modification is well adapted for use where great tensile strength is not essential.

50 In Fig. 8 the main support or upright B² is formed of two channels 55, the webs 25 of which are in abutting relation. Each channel is provided with the longitudinally extending flange 26, against which the panels 55 D rest, and flanges 27, so that, in cross section, this modification resembles a T section. The webs 25 are provided with ways 28, in this modification, formed to receive the countersunk heads 56 of bolts 51, the usual 60 retainers E being provided. This modified form of main support is well adapted for use in tunnel works where it is necessary to draw one section of the form into operative relation to the other, and for which purpose, 65 the bolt 57, having a nut 58 is provided, this

bolt passing transversely through the webs of the channels.

Pursuant to one of the principal objects of my invention, that is, to utilize standard rolled steel sections, where expansion occurs, or for the end of a form, as shown to the right of Fig. 2, the upright B³ may comprise a channel 59 provided with flanges 26 and 27, and against the former of which panel D rests; the usual retainer E and securing device F, which latter also holds a Z-bar 60, one flange of which abuts with the web of channel 59, while the other flange is in engagement with the outer face of the end panel D, this panel also resting against the web of the channel, as clearly shown in the drawings. If desired, the turn buckle bolts 61 may be substituted for the usual bolt 51, and by the aid of a turnbuckle 62, joining bolt 61, the forms may be held rigid 85 and drawn tightly into alinement. Likewise, the exterior corner upright B⁴ may comprise an angle 63, the interior face of which forms angular walls of the "hollow"; and suitable Z-bars 64, held in place by 90 suitable securing devices F, in such a manner that one leg of each Z-bar abuts with one flange of the angle 63, while the other flange of the Z-bar engages the exterior face of panel D, this panel also engaging a 95 portion of the angle section 63, as clearly shown to the left of Fig. 2. The interior corner main support or upright B⁵ may comprise the same elements as upright B⁴ but disposed differently. It is built up of 100 angle sections 65 the exterior faces of which form wall portions of the "hollow" while the panels D are held in place by Z-bars 66 and securing devices E in a manner similar to that described in connection with form B⁴. 105 The Z-bars are held in place with one flange in abutting relation to the interior face of the angle sections 65, with the other flange of the B section resting against the face of the panel.

110 In some sections of the country it may be desirable to utilize rather light rolled or pressed steel sections in conjunction with wood fillers or posts, and referring now to the application of my invention to such a combination, uprights B⁶, to be interposed between corner uprights, may comprise a wood core 69, creosoted to preserve and waterproof the same, and to which are secured angle sections 70, one flange of each section, that designated 71, resting against the face of core 69, while the other flange 72 receives the side portions of panel D. Each flange 71 is provided with the usual ways 28, which receive the bolts of securing devices F, co-operating 115 with retainer E for holding the panel in engagement with flange 72. The filler 69 is routed out, as indicated at 73, and more specifically shown in Fig. 21, to the rear of way 28 to make room for the head of bolt 120 125 130

51, forming a part of the retaining device F. A plate 74 is secured to the face of core 69 adjacent the "hollow" of the form, if desired. In the modification shown in Fig. 14, the main support or upright B⁷ is similar to that shown in Fig. 13, with the exception that it is relatively narrower, and the way 28 is continuous transversely of the main body portion of the structure, a single bolt 51 serving to retain two of the elements E in place. In both forms B⁶ and B⁷, the angle sections 70 may be secured to the core by means of bolts 75 passing transversely through the structure, and having nuts 76 turned tightly against the flanges 71.

With forms using the wood core, the corners may be constructed by providing an upright core 77 to the adjacent faces of which are secured angle sections 78, so disposed that the margins of both exterior faces of said sections are in abutting relation, as clearly shown in Fig. 9. One flange 79 of each section 78 is secured to the core 77 as by bolts 80 and nuts 81, and said flanges are provided with the usual way 28 for receiving the securing devices F, coöperating with retainers E, and in conjunction with the other flange 82 of sections 78, for holding the panels D in place. The cores are also routed, as indicated at 83 for the heads of bolts used and forming a part of the securing devices F.

If desired, as shown in Fig. 12, the bolts 51 may be provided with countersunk heads 84, and under which conditions the routing 83 as shown in Fig. 9 is not necessary.

Interior corners utilizing wood cores may be formed as shown in Figs. 16 and 17, where the wood core is indicated by character 85. Angle sections 86 are secured to adjacent faces of the core but with the face of one flange 87 in alignment with, or in close proximity to the opposite face from that to which the other section 86 is secured. The other flange 88 of each section 86 is provided with the usual way 28 to accommodate the securing device F, also coöperating with retainer E, for holding the panels D in place. The core 85 is routed out as indicated at 89 to receive the bolt heads of bolts 51. The sections 86 may be secured to the core 85 as by bolts 90 and nuts 91, as clearly shown in Fig. 19, and under which conditions the core 85 may be provided with a recess 92 for the heads of bolts 90, these recesses being closed by means of an angular plate 93, secured to the core 85 in any suitable manner.

It may be desirable to further modify this combination of wood and metal in the provision of main supports such as is shown in Fig. 19, B¹¹ being a form of supports to be interposed between corner supports, and comprising a core 94 of wood, with flanges 95 adjacent the faces thereof, flanges 96 ex-

tending longitudinally of the core 94, and against which the panels D abut, being of one continuous sheet of metal which also covers the face of the core at the "hollow" of the assembled form. Thus, the core 94 70 may be placed between the flanges 95, on the ground, and through which extend the usual ways 28 for securing devices F and the retainers E, which are here shown as formed of sheet metal, the end portions of 75 which are doubled upon itself to provide the two flanges 97 and 98, the latter of which engage the panels. With regard to the modification of the corner posts for the exterior of the form, it comprises the core 80 99 of wood with a shell or casing of sheet metal 100 about the core and having its end portions doubled upon itself, at right angles, forming flanges 101 against which the panels D abut. The core, as well as the shell is 85 provided with the usual way 28, and the securing devices are here shown comprising bolts 51 extending entirely through the core and shell portions, and receiving the nuts 52 adjacent retainer E which is formed as 90 described in connection with the support B¹¹. The internal corner support or upright may comprise a wood core 102, with a casing of sheet metal 103, doubled upon itself 95 adjacent the center portions, providing flange 104, and having one end portion doubled upon itself providing flange 105, the ends of the sheet metal joining as indicated at 106. The core 103 is recessed as at 107, to the rear of the ways 28 for the 100 securing devices F, which coöperate with the securing devices E.

It is to be understood that, in connection with any of the main supports or uprights, utilizing wood as a core, or to give tensile 105 strength to the members, the metallic portions can be formed and assembled into operative relation to the wood cores obtained at the locality in which the metallic portions are shipped. In this way the members of 110 the forms can be adapted to the particular work, and to withstand the load.

The invention is susceptible of many changes and modifications which may be made in detail, without departing from the 115 spirit or scope of my invention; but,

I claim:

1. In forms for concrete construction, the combination of main supports in spaced relation, each support provided with a longitudinally extending flange and a plurality of ways extending through the body of said supports, each way being substantially L-shaped with the walls of one portion inclined toward and with the closed end thereof of nearest said flange, panels in abutting relation with the flanges of said supports with their sides adjacent said ways, angle bars in abutting relation with the outer faces of said panels, each bar provided with perfora- 130

tions to aline with the said ways in said supports, and securing devices passing through said ways and alined perforations.

5 2. In forms for concrete construction, the combination of main supports in spaced relation, each support provided with a flange extending longitudinally of and at each side, and a plurality of ways extending through the said body of each support, each way being substantially L-shaped with the walls of one portion inclined toward and with the closed end thereof nearest said flanges, panels in abutting relation with the flanges of said supports with their sides adjacent said ways, 10 angle bars in abutting relation with the outer faces of said panels, each bar provided with perforations to aline with the said ways in said supports, and securing devices passing through said ways and alined perforations.

15 20 3. A form for concrete construction comprising in combination, a base, uprights secured thereto in spaced relation, each upright provided with a longitudinally extending flange and a plurality of ways extending through the body of said upright, each way being substantially L-shaped with the walls of one leg inclined toward and with the closed end thereof nearest said flange, panels in abutting relation with the flanges of said uprights with their sides adjacent said ways, angle bars in abutting relation with the outer faces of said panels, each bar provided with perforations to aline with the said ways in said uprights, and securing devices passing through said ways and alined perforations.

4. A form for concrete construction comprising in combination, a base, uprights secured thereto in spaced relation, each upright provided with a flange extending longitudinally of and at each side and a plurality of ways extending through the body of the uprights, each way being substantially L-shaped with the walls of one of the legs inclined toward and with the closed ends thereof nearest said flanges, panels in abutting relation with the flanges of said uprights with their sides adjacent said ways, angle bars in abutting relation with the outer faces of said panels, each bar provided with perforations to aline with the said ways in said uprights, and securing devices passing through said ways and alined perforations.

5. In forms for concrete construction, the combination of main supports comprising rolled metal sections each including a web and a flange extending longitudinally thereof, each section provided with a plurality of transverse L-shaped ways in its web with the walls of one leg of each way inclined toward and with its closed end nearest said flange, panels in abutting relation with the flanges of said supports with their sides adjacent said ways, angle bars in abutting re-

lation with the outer faces of said panels, each bar provided with perforations to aline with the said ways in said supports, and securing devices passing through said ways and alined perforations.

6. In forms for concrete construction, the combination of main supports comprising rolled metal sections each including a web and flanges extending longitudinally of and at each side of said webs, each section provided with a plurality of transverse L-shaped ways in its web, with the walls of one leg of each way inclined toward and with the closed end thereof nearest said flanges, panels in abutting relation with the flanges of said supports with their sides adjacent said ways, angle bars in abutting relation with the outer faces of said panels, each bar provided with perforations to aline with the said ways in said supports, and securing devices passing through said ways and alined perforations.

7. In forms for concrete construction, the combination of a base, uprights detachably secured thereto in spaced relation each upright formed of a rolled metallic section including a web and a flange extending longitudinally thereof, each section provided with a plurality of transverse L-shaped ways in its web, with the walls of one leg of each way inclined toward and with the closed end thereof nearest said flange, panels in abutting relation with the flanges of said uprights with their sides adjacent the ways, angle bars in abutting relation with the outer faces of said panels, each bar provided with perforations to aline with the said ways in said uprights, and securing devices passing through said ways and alined perforations.

8. In forms for concrete construction, the combination of a base, uprights detachably secured thereto in spaced relation, each upright formed of a rolled metal section including a web and flanges extending longitudinally of and at both sides of said web, each section provided with a plurality of transverse L-shaped ways in its web with the walls of one leg of each way inclined toward and with the closed end thereof nearest said flange, panels in abutting relation with the flanges of said supports with their sides adjacent said ways, angle bars in abutting relation with the outer faces of said panels, each bar provided with perforations to aline with the said ways in said supports, and securing devices passing through said ways and alined perforations.

9. In forms for concrete construction, the combination of main supports, comprising rolled metal sections each including a web and a flange extending longitudinally thereof, and a plurality of ways in each web with the opposite walls of each way inclined toward said flange, said supports being dis-

- posed in spaced relation, panels in abutting relation with the flanges of said supports with their sides adjacent said ways, angle bars in abutting relation with the outer faces 5 of said panels, each bar provided with perforations to aline with the said ways in said supports, and securing devices passing through said ways and alined perforations.
10. In forms for concrete construction, the combination of main supports comprising rolled metal sections including a web and flanges extending longitudinally thereof and at both sides of said webs, each section provided with a plurality of ways in its web 15 with the opposite walls of each way inclined toward said flanges, said supports being disposed in spaced relation, panels in abutting relation with the flanges of said supports with their sides adjacent said ways, angle 20 bars in abutting relation with the outer faces of said panels, each bar provided with perforations to aline with the said ways in said supports, and securing devices passing through said ways and alined perforations.
25. 11. In forms for concrete construction, the combination of a corner post, angle sections secured to and longitudinally of adjacent faces of said post with the outer edges common to both flanges of each section in abutting relation, and angle sections adjustably secured to the flanges of said first-mentioned angle sections next adjacent to said corner post, with a flange of each of said second-mentioned angle sections in parallelism to 30 the projecting flange of said first-mentioned angle section, but in spaced-apart relation.
12. In forms for concrete construction, the combination of a corner post, angle sections secured to and longitudinally of adjacent 35 faces of said corner posts with a flange of each section in parallelism with the face of said post opposite to that to which the other section is secured, and angle sections adjustably secured to the flanges of said first-mentioned angle sections next adjacent to 40 said corner posts, with a flange at each of said second-mentioned angle sections in parallelism to the projecting flanges of said first-mentioned angle section but in spaced- 45 apart relation.
50. 13. In forms for concrete construction, the combination of a main support comprising angle sections formed from sheet metal and bent to provide a longitudinal flange and a web, angle sections disposed with one flange 55 abutting said web and the other flange in parallelism to but spaced apart from the said flange of said support, and means for securing said second-mentioned angle section to the web of said support.
14. In forms for concrete construction, the combination of a main support forming a casing and comprising angle sections made from sheet metal and bent to provide a longitudinal flange and a web, angle sections 60 disposed with one flange abutting said web and the other flange in parallelism to but spaced apart from said flange of said support, and means for securing said second-mentioned angle section to the web of said support.
15. In forms for concrete construction, the combination of a main support forming a casing and comprising angle sections bent from sheet metal to provide a longitudinal 65 flange and a web, angle sections disposed with one flange abutting said web and the other flange in parallelism to but spaced apart from said flange of said support, means for securing said second-mentioned angle sections to the web of said support, and a wood filler for said main support.
16. In forms for concrete construction, the combination of three or more I-sections disposed in spaced relation with webs facing 70 each other, the web of each I-section provided with a plurality of angle-shaped ways the end portions of said ways being nearest the flanges of the section, panels extending between the webs of adjacent I-sections and 75 abutting one flange of each, an angle section for each flange of each I-section against which said panels abut, said angle sections 80 engaging the outer faces of the panels and each provided with a plurality of perforations to aline with the said ways in said webs, and securing devices passing through 85 said ways and alined perforations.

FRANK P. KEMON.
